COMBINED RAILWAY CONTAINER AND CAR

John R. Cooney, Dyer, Ind., assignor to Pullman Incorporated, a corporation of Delaware

Filed Aug. 29, 1961, Ser. No. 66,528

Term of patent 14 years

(Cl. D66—1)

FIG. 1 is a perspective view of a combined railway container and car showing my new design, the door in open position having the same appearance as the one in closed position; and

FIG. 2 is a top plan view thereof showing the transverse cross sectional contour of the end walls.

The sides and ends of the container and the car not shown in FIG. 1 are substantially the same as those shown.

The essential features of my design reside in the portions shown in full lines with the lading shown in broken lines being included for illustrative purposes only.

The characteristic feature of my new design resides in the end walls of convex arcuate transverse cross section in combination with the fenders over the wheels as shown.

I claim:

The ornamental design for a combined railway container and car, substantially as shown and described.
